UNITED STATES PATENT OFFICE.

JOSEPH E. BURTLE, OF SPRINGFIELD, ILLINOIS.

PNEUMATIC HAMMER.

968,236.

Specification of Letters Patent. Patented Aug. 23, 1910.
Application filed August 26, 1908. Serial No. 450,400.

To all whom it may concern:

Be it known that I, JOSEPH E. BURTLE, a citizen of the United States, residing at Springfield, in the county of Sangamon and State of Illinois, have invented a new and useful Improvement in Pneumatic Hammers, of which the following is such a full, clear, and exact description as will enable others skilled in the art to which it appertains to make and use my said invention.

This invention relates to pneumatic hammers and the purposes of the invention are to provide in communication with the cylinder of the hammer, a valve controlling the admission of air to the cylinder and the discharge of air from the cylinder; to provide means for operating said valve; and to provide other new and useful features of construction, shown in the drawings, and hereinafter described and finally recited in the claims.

Referring to the drawings in which similar reference numerals and characters designate like parts in the several views: Figures 1 and 2 are respectively a side elevation and front elevation of the complete machine. Fig. 3 is a transverse section on the zig-zag line X. X. of Fig. 1. Fig. 4 is an enlarged front elevation of the cylinder and connected parts. Fig. 5 is a vertical longitudinal section on the line Y. Y. of Fig. 4. Fig. 6 is a horizontal section on the line Z. Z. of Fig. 4. Fig. 7 is an enlarged horizontal section on the line W. W. of Fig. 1. Fig. 8 is an enlarged horizontal section on the line V. V. of Fig. 1, and Fig. 9 is an enlarged horizontal section on the line U. U. of Fig. 1, looking upward.

The main structure is of cast iron and comprises a vertical standard 1; secured on a suitable horizontal base 2. Braces, 3 and 3' are integral with the standard 1. The brace 3, extends through an opening 4', in one wall of the anvil block 4; and the lower end of the brace rests firmly upon the upper surface of the base 2, and gives stability to the standard; and that part of the brace projecting into the anvil block facilitates the placing of the anvil block centrally under the hammer head, and also serves to prevent lateral displacement of the anvil block. Braces 5 integral with the upper part of the standard, lie under and strengthen the box member 6, which is also integral with the standard. A complementary box member 7 is secured on the member 6 by bolts 8. The

shaft 9 turns in the box formed by the members 6 and 7. A crank disk 10, and a pulley, 11, are secured on the shaft, 9. One end of the connecting rod, 12, fits on a wrist pin, 13, on the crank disk 10.

A bracket 14, integral with the standard 1, supports the cylinder 15, and the cylinder is connected with the bracket by bolts 15'. Slidable cup-shaped pistons 16, and 17, fit in the bore of the cylinder 15. It is found in practice that the air compressed in the cups of the pistons serves to keep the pistons in alinement and the heat resulting from the sudden compression of air within the cups serve to cause a degree of expansion of the rims of the cups, sufficient to prevent leakage of air around the pistons, thereby avoiding the necessity for using packing rings on the pistons.

A block 18, is secured on the piston 16 and a pin 19 connects the rod 12 with the block 18. The hammer-rod 20, is securely connected with the piston 17. The hammer head 21, is detachably connected with the lower end of the rod 20. In the drawings I have shown a dove-tail lug on the hammer head, fitting in a corresponding channel in the lower end of the rod; but any other suitable connection may be used.

An opening 15^a extends through the wall of the cylinder 15. A nipple 22 screws into the opening 15^a and connects the valve body 23 with the cylinder 15. A gate 24 is slideable within the valve body 23. A vertical stem 25 is fixed on the gate 24.

Parallel vertical rods 27 are slideable in holes 26^a in the guides 26. The lower parts 27^b of the rods 27 converge and both are secured on the cam bar 28 by rivets 28^a, or equivalent means. A cross bar 29 is secured on the rods 27, and the upper part of the stem 25 is connected with the cross bar. Springs 30 surround the rods 27 between the lower guide, 26, and the cross bar 29 and act to support the cross bar 29 and the gate 24 connected therewith, in the raised position shown in Fig. 5, so that normally the valve is open. When the rods 27 are slid downward, and the springs are compressed, the gate 24 will have moved downward, and the valve will be closed, and when the pressure is removed, the springs will act on the bar 29 to raise the gate, and open the valve. Nuts 27^a on the rods 27 may be screwed upward or downward on the rods, to limit the vertical movement of the rods.

In practice, it is sometimes desirable to so adjust the parts that the valve may close partially but not completely. This is attained by screwing down the nuts 27^a so that 5 they will strike against the upper surface of the upper guide 26, and stop the rods 27 before they have moved downward far enough to completely close the valve; the extent of the closing of the valve being determined by the position in which the nuts 10 are set.

An approximately semi-circular bottom plate 31 has a radial channel 31^a and is secured on the lower end of the cylinder by 15 bolts 32. A latch 33, having a longitudinal slot 33^a, and a chisel shaped end 33^b is slideable in the channel 31^a. A toothed plate 34 is secured on the side of the rod 20 adjacent to the end of the latch 33, and the end of 20 the latch engages with the teeth of the plate to support the rod 20 and the connected parts. A roller 35 is mounted to turn in the slot 33^a of the latch 33.

Brackets 36 are secured on the cylinder. 25 A lever 37 oscillates on a pin 36^a extending through the brackets. The lower end of the lever 37 fits in the slot 33^a and is connected with the latch 33 by a pin 37^a and the upper end of the lever is connected with the bolt 38 by a pin 38^a. The bolt 38 is slideable in a hole 15^b in the wall of the cylinder 15. A spring 39 surrounds the bolt 38 and acts 30 against the upper end of the lever 37 to cause the lever to slide the latch, 33 inward and hold the end 33^b of the latch in engagement with the teeth of the plate 34.

A pedal 40 is mounted to oscillate on bolts 41 which connect the pedal with the base of the standard. Levers 42 are oscillative on 40 bolts 43 which connect the levers with the standard 1 and the front ends of the levers are connected with the cam bar 28 by a pin 28^a. Rods 44 connect the levers 42 with the 45 pedal 40 in such manner that the depressing of the pedal 40 will cause the levers to slide the cam bar 28 downward, and thereby simultaneously move the gate, 24, and the latch 33 as will now be described.

Near the lower end of the latch bar 28 is 50 a cam 28^b which acts on the wheel 35 to slide the latch 33 outward when the latch bar moves downward. The valve being normally open, it is necessary to close or partially close the valve so that the air within 55 the cylinder may be compressed to render the hammer effective. The force of the blow may be regulated according as the valve is

closed or partially open. If the valve is completely closed, the hardest blow will be struck; if it is slightly open, a somewhat 60 lighter blow will be struck, and if it is more open, a still lighter blow will be struck. The operator keeps his foot on the pedal 40 and controls the operation of the valve by pressing on or removing pressure from the pedal, 65 and is thereby enabled to accurately gage the force of the blow according to the nature of the work.

Having fully described my invention, what I claim as new and desire to secure by 70 Letters Patent, is:

1. In a pneumatic hammer, the combination of a cylinder, a primary piston and a secondary piston slideable within said cylinder, a rod connected with said secondary 75 piston, a toothed plate fixed on said rod, a valve-body having an opening communicating with the interior of said cylinder between said primary and secondary pistons, a gate slideable in said valve body to control 80 the opening thereof, guides fixed on said cylinder, rods slideable in bearings on said guides, a cross-bar connecting said rods and connected with the stem of said gate, springs surrounding said rods and acting to lift 85 said rods to raise said gate, a cam-bar connected with said rods and having a cam, levers connected with said cam-bar, a pedal pivotally connected with the main structure, connecting rods connecting said levers with 90 said pedal, a latch adapted to engage the teeth of said toothed plate, a roller mounted on said latch and adapted to be engaged by the cam of said cam-bar, and a spring acting to normally hold said latch in engagement with the teeth of said toothed plate. 95

2. In a pneumatic hammer, the combination of a cylinder, pistons slideable within said cylinder, a valve body having an opening communicating with the interior of said cylinder between said pistons, a gate slideable in said valve body, guides secured on said cylinder, rods slideable in said guides and connected to operate said gate, and nuts on said rods adjustable to limit the movement 100 of said gate.

In witness whereof I have hereunto subscribed my name at the city of Springfield, Illinois, this 8th day of Aug. 1908.

JOSEPH E. BURTLE.
